United States Patent Office.

CHARLES G. WILSON, OF BROOKLYN, NEW YORK.

Letters Patent No. 94,682, dated September 7, 1869.

IMPROVED FURNITURE-CASTER.

The Schedule referred to in these Letters Patent and making part of the same.

To all whom it may concern:

Be it known that I, CHARLES G. WILSON, of Brooklyn, in the county of Kings, and State of New York, have invented a new and useful Improvement in Furniture-Casters; and I do hereby declare that the following is a full, clear, and exact description thereof, which will enable others skilled in the art to make and use the same, reference being had to the accompanying drawings, forming part of this specification, in which—

The figure is a detail vertical section of my improved caster.

My invention has for its object to furnish an improved furniture-caster, which shall be so constructed and arranged that it will allow the table or other article to which it may be attached, to be moved freely in any direction, and which shall at the same time be simple in construction, strong, durable, and not liable to get out of order; and consists in the caster constructed with a sphere and a series of small balls, freely moving over the top thereof, as hereinafter more fully described.

A is the body of the caster, in the upper end of which is formed a socket, to receive the end of the leg of the table or other article of furniture, or a tenon formed upon said leg.

The caster may be secured in place by means of a screw-thread, cut upon the inner surface of said socket, or by means of screws or rivets, passing through the sides of said socket.

In the bottom or lower part of the body A is formed a hemispherical or cup-shaped socket, in which are placed a number of small balls, B, and a single large central ball, C. The number of the small balls B must be such as to nearly but not quite fill the space between the ball C and concave surface of the cavity in which it is placed. The ball C must be of such a size

that its lower side may project below the lower end of the body A, and it is kept in place by the cap D, which screws upon the lower end of the said body, as shown in the figure.

The cap D has a hole formed through it, through which the lower part of the ball C projects; said hole being made of such a size that the ball C, when supporting the article of furniture to which the caster may be attached, may not touch the said cap, and at the same time so small that the said ball C cannot drop through it when the said article is raised from the floor, the friction being entirely borne by the balls B and C, rolling upon each other, and upon the concave surface of the cup in which they are placed.

The outside of the caster may be made of any desired shape, or may be made to correspond with the style of carving with which the article of furniture to which it may be attached is ornamented.

Having thus described my invention,
I claim as new, and desire to secure by Letters Patent—

The improved furniture-caster above described, formed by the combination of a solid sphere, rolling freely in its socket, a caster-body, provided with a hemispherical concavity and suitable cap, and a series of frictional balls arranged around the surface of the said sphere, and freely moving over the entire upper surface of the caster-ball, when brought in frictional contact with the same, all substantially as shown and described.

The above specification of my invention signed by me, this 9th day of July, 1869.

CHARLES G. WILSON.
